UNITED STATES PATENT OFFICE

DUDLEY D. LEVY, OF NEW YORK, N. Y.

MEASURING AND SELF-CLOSING DEVICE FOR COLLAPSIBLE TUBES

Application filed January 28, 1928. Serial No. 249,509.

This invention relates to collapsible tubes for shaving cream or the like and includes means whereby the tube is closed as a measured quantity of the tube contents is extruded 5 for use.

The object of the invention includes the provision of an efficient but simple closing means for tubes of the kind specified whereby a definite quantity of the creamy or pastry 10 contents is exposed for use.

Another object includes the provision of a tube having a tapered opening with a plug fitting said opening and having an anchoring stem extending through said opening for 15 depressing the plug into the tube preparatory to obtaining a definite quantity of the creamy or pasty contents of the tube. That is to say, I provide, in a collapsible tube having a tapered opening, means whereby the tube is 20 sealed when the measured quantity has been extruded.

Other objects will appear hereinafter and I obtain these objects by the construction shown in the accompanying drawing in 25 which—

Figure 1 is a top plan view of a tube to which my invention is applied;

Fig. 2 is a side elevation of a collapsible tube, partly in section on line 2—2 of Fig. 1, 30 to show the fit of the closing device or plug;

Fig. 3 is a view similar to that of Fig. 2, except that the closing plug is down and ready to mete out a definite quantity; and

Fig. 4 is a sectional view of the plug showing a flexible handle attached thereto.

The same numerals of reference refer to like parts in the several views.

My invention is particularly adapted for shaving creams, tooth pastes, cold creams, 40 and like pasty or creamy substances in collapsible containers 10 and having a tapering shoulder 11 which terminates in a neck 12. The opening through said neck is somewhat smaller at the outer end 13' than at the inner 45 end 14. Consequently the opening in the neck of said tube is tapering as is shown in Figs. 2 and 3.

Within the tapered opening there is fitted the self-sealing plug 13. This plug is, in 50 general, bell-shaped with the outer tapered

wall thereof adapted to fit the tapered inner wall in the neck. The tube is provided with a handle 15 which terminates in a cross-piece 16. The handle may be rigid and formed as a part of the plug or it may be a flexible 55 handle 17 properly anchored at 18 in the head of the plug. The flexible handle 17 has a loop 19 by which the plug is pushed down into the contents in the tube. This loop is widened out when the plug is in place so 60 that the plug is anchored in the neck opening. In the solid form of handle (Figs. 2 and 3) the cross-bar 16 is long enough to anchor the plug in the neck opening so that when the plug is depressed or open, as in 65 Fig. 3, the cross-piece rests on the edge 13' of the tapered neck. For assembling the cross-piece may be made removable or it may be bent to slip through the neck.

The plug 13 is shown hollow and in the 70 shape of a truncated cone, but it is not confined to the specific shape shown. And, while I have shown and described specific forms of anchored plugs to be fitted in the tapered neck of a collapsible tube, I do not thereby desire 75 to be understood as having thus limited myself, except as stated in the appended claims.

The operation of my device is simple and readily understood. Assuming that it is desired to obtain a definite quantity of shaving 80 cream, for example, in that event plug 13 is pushed into the tube a definite distance depending upon the quantity of cream required and extruded as stated below. If the full measure is desired the handle will be pushed 85 down until the cross bar 16 or the loop 19 rests on the upper edge 13' of the neck 12. The tube is now collapsed by squeezing and the outward flow of the cream will carry the plug into its sealed position (Fig. 2) carrying 90 with it the extruded core of cream 20 which surrounds the stem 15—or 17 if the flexible handle is used. In some instances I prefer the flexible handle or stem as it can be flexed 95 to remove the cream. The loop of the flexible stem serves also as a means for suspending the tube from a nail or hook when not used.

I find that my device is very convenient and that the tapered plug is self-sealing and very 100 effectively closes the tube.

Having now described my invention, what I claim is:

1. In a collapsible tube, a shoulder terminating in a neck having an elongated tapered opening therethrough, a tapered hollow plug fitted to seal said neck when the tube is compressed to extrude a quantity of the contents of said tube through said opening, and a stem extending outwardly from and rigidly anchored to said plug, said stem having a stop on its outer end for limiting the inward movement of said plug.
2. A collapsible tube having a tapering opening, a hollow plug open at the inner end and having a handle comprising a stem and a cross-member rigidly formed near the outer end of said stem anchored in said opening whereby the plug may be displaced into the contents of the tube and a measured quantity of said contents extruded with the movement of the plug in closing the said opening.
3. A tube for creamy or pastry materials, said tube having an elongated, tapered, outwardly converging opening and a bell-shaped plug to movably fit said opening, a handle rigidly mounted on said plug and terminating in a loop at its outer end whereby said plug is movably anchored in said opening and displaced a predetermined distance into the tube, whereby an approximately measured quantity of the material may be extruded from the tube upon each successive operation of said handle.
4. In a collapsible tube, a neck having a tapered opening converging outwardly, a tapered hollowed plug movably anchored in said neck, an inner end of said hollow plug open to direct contact with the contents of said tube, a stem on said plug extending outwardly, said stem having an outer stop for limiting the inward movement of the plug and thereby determine the amount of discharge for each operation of said plug.

In testimony whereof I have hereunto set my hand on this 23d day of January, A. D. 1928.

DUDLEY D. LEVY.
